AUTOMOBILE DOOR

Filed April 11, 1923

2 Sheets-Sheet 2

UNITED STATES PATENT OFFICE.

JOSEPH LEDWINKA, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

AUTOMOBILE DOOR.

Application filed April 11, 1923. Serial No. 631,256.

My invention relates to improvements in automobile doors and has to do, more particularly, with doors for use in connection with automobile bodies and constructed entirely 5 of metal.

The principal object of my invention is to provide an automobile door constructed entirely of metal and which is very light but, nevertheless, stiff, strong and durable so as 10 to withstand satisfactorily the hard usage to which such doors are usually subjected.

A further object of my invention is to provide an all-metal door of such construction as to permit the use of aluminum, or other 15 light metals, throughout practically the entire door construction.

Another object of my invention is to provide an all-metal door construction including a door frame having an improved mounting 20 for the door latch mechanism.

A further object of my invention is to provide an all-metal door construction including a cast metal frame to which a sheet metal door panel is applied and secured.

25 Further objects, and objects relating to details and economies of operation and construction, will definitely appear from the detailed description to follow. In one instance, I accomplish the objects of my invention by 30 the devices and means described in the following specification. My invention is clearly defined and pointed out in the appended claims. A structure constituting a preferred embodiment of my invention is illustrated in 35 the accompanying drawings, forming a part of this specification, in which:

Fig. 1 is a view in elevation of a door embodying my invention, the view being taken 40 looking at the outer side of the door.

Fig. 2 is a view in elevation looking at the inner side of the door.

Fig. 3 is a view in elevation of the door frame with the door panel removed therefrom, this view being taken looking at the 45 outer side of the frame, that is, the side nearest to the door panel.

Fig. 4 is a detail, sectional view, taken on the line 4—4 of Figs. 2 and 3, and showing the connection between the upper marginal por-

tion of the door panel and the frame and, also, 50 the mounting for the latch mechanism.

Fig. 5 is a detail, sectional view, taken on the line 5—5 of Figs. 2 and 3, and showing the connection between the upper marginal portion of the door panel and the door frame. 55

Fig. 6 is a detail, sectional view, taken on the line 6—6 of Figs. 2 and 3, and showing the connection between the door panel and one edge of the door frame and the means provided in the door frame for mounting a 60 hinge.

Figs. 7 and 8 are detail, sectional views, taken on the lines 7—7 and 8—8, respectively, of Figs. 2 and 3, and showing the connections between the lower portions of the door panel 65 and the door frame.

Fig. 9 is a detail, sectional view, taken on line 9—9 of Figs. 2 and 3, and showing the formation of the door frame to receive a curtain rod, and 70

Fig. 10 is a detail, sectional view, taken on line 10—10 of Fig. 3, and showing the means for connecting the male dovetail member to the door.

In the drawings, the same reference numerals refer to the same parts throughout the several views and the sectional views are taken looking in the direction of the arrows at the ends of the section lines. 75

All-metal automobile doors, as heretofore 80 most commonly constructed, have consisted of a pair of sheet metal panels secured together with the body portion of one panel offset from the other, so as to form a chamber between the two panels, and the outer 85 panel secured to the inner panel by folding or bending the edge portions of the outer panel over a projecting lip at the edge of the inner panel. These doors have been given the requisite strength and stiffness by pressing the inner panel into such shape that it acts as a reinforcing member, reinforcing and strengthening the outer panel, which is curved and finished to conform to the contour of the automobile body. In accordance with 90 my present invention, I propose to employ a single sheet metal panel and to apply and secure the same to a metal frame in such 95

manner, and with a metal frame of such character and construction, as to secure lightness as well as stiffness and strength in the door structure. I also propose to provide 5 an adequate mounting for the latch mechanism carried by the door and, to accomplish this purpose, I propose to provide the metal door frame with suitable seats formed to receive and support the latch plate of the latch 10 mechanism, the frame being suitably recessed at this point to receive the latch mechanism and to permit it to work through the edge of the door. I also propose to provide the frame with a bearing in which a latch operating spindle may be journaled if desired. 15 I also propose to form the upper edge of the door with an attractive finish and, at the same time, provide means to which the usual upholsterty for the inner surface of the door 20 may be fastened. To accomplish this, I propose to so construct the top member of the door frame as to permit the door panel to fold smoothly over the upper edge thereof, and I provide means on said top member to receive and form a support for an upholsterty tacking strip, and I utilize said strip also as 25 a means for securing the folded-over upper edge of the panel. It is customary to provide a curtain rod carried by the upper portion 30 of the door, near the free edge thereof, to which the storm curtains may be fastened, so that a section of the storm curtains may be moved aside, with the opening of the door, to provide ingress and egress from the automobile without unfastening the storm curtains. 35 It is among the purposes of my invention to provide improved means, in an all metal door construction, for supporting such curtain rods and, to this end, I propose to 40 provide the door frame with a socket or seat to receive a curtain rod. It is another purpose of my invention to provide means for mounting the hinges on the door of such a nature that the means for fastening the hinges 45 to the door will be readily accessible, so that the hinges can very easily and quickly be removed.

In carrying out my invention, in one practical form of embodiment thereof, I employ 50 a door frame, 11, the shape of which is determined by the shape or contour which is to be given the door. In the example shown, the door frame is of generally rectangular shape and, along its bottom and sides, is provided 55 with a marginal web, 9, which extends transversely to the plane of the door. This web constitutes the bottom and vertical side edges of the door structure. The inner edge of the web, 9, is formed with a flange member 60 or extension, 16, at right angles to the web body. The purpose of this flange member or extension is to impart stiffness and strength to the door frame. The web, 9, is formed, at intervals, with enlargements or 65 bosses, 12, to receive screws, 14, by which

batten strips, 13, are secured against the outer edge surface of the web. These enlargements or bosses extend transversely of the web and also serve to increase the strength and stiffness of the frame. The door panel, 70 10, is applied to the outer surface of the frame and is secured thereto in any suitable or convenient manner. In the arrangement shown, the batten strips, 13, extend laterally beyond the outer edge surface of the web, 9, and the 75 bottom and vertical side edges of the door panel are bent over and clinched upon the laterally-extending edges of the batten strips, as indicated at 15, thereby not only covering and concealing the door frame, 11, but also 80 the batten strips and the means by which said strips are secured to the frame. This structure also provides the door with a marginal stop flange to overlie the adjacent edge portions of the automobile body which form the 85 door opening.

Several important major advantages grow out of this organization of elements. First, it is not practicable to cast metal in extremely thin sections. It is nevertheless desirable to 90 have the marginal stop flange or overlap of the door of very thin section so that the exterior of the body may be free from deep recesses and pockets at the meeting lines of the doors and the body paneling. The thin rolled 95 metal batten strips 13 take the place of what might be a thin flange on the webs of the one-piece cast-metal skeleton frame. The difficult and impracticable casting of thin flanges is therefore avoided. Instead of locating a 100 cast flange at this point, therefore, the cast flange 16 is located on the inner face of the frame. Here, it strengthens the cast frame to the same extent as it would if formed on the outer edge of the body web, but here it 105 may be made of thick section, since thinness is of no especial moment. Here, too, it is of structural, as well as, strengthening advantage in that it establishes the inner face of the door and forms a mounting for the inner 110 panel or upholsterty. Still further, the body web 9 together with the inner face flange 16 115 constitute an angle section for the top, bottom and side rails of the one-piece, integral structure, and together with the batten strips 13 on the bottom and side rails, and together with the inturned integral flange 18 on the top rail, they constitute the frame section a Z-section, of particular advantage in that the transversely extending web of the section constitutes the stop flange or overlap and the inner arm 16 constitutes the foundation for the upholsterty or inner panel attachment, so 120 that such a section is an ideal combination for lightness and adaptability.

In order to provide a neat and slightly appearing finish for the upper edge of the door, the surface of the top member or rail of the door frame, against which the door panel is applied, may be given any desired shape in 130

- transverse section. In the form shown, the outer surface of the frame top rail or member which receives the panel is curved inwardly, as indicated at 18, and the panel is applied 5 to said curved surface. The top edge of the panel may be folded over the inner edge of the frame top rail and secured thereto in any suitable or convenient manner. In the arrangement shown, to which my invention is 10 not to be limited or restricted, I form the top rail of the frame with an inwardly opening channel, 19, into which the folded or bent over upper edge of the door panel is received. The bent over edge of the door panel may be 15 wedged into the channel, 19, and held therein in many different ways. A simple arrangement is shown wherein the upholstery tacking strip, 35, is employed for this purpose. This strip, in the structure shown, is fastened to the top member or rail of the door frame by screws or other fastening devices, 37, and the upholstery, 38, usually employed to cover the inner face of the door, is secured 20 at its upper edge to said strip.
- 25 If desired, and in order to still further strengthen the top rail of the door frame, said rail may be formed with a longitudinally-extending, outwardly-opening channel, 17, as shown in Fig. 5.
- 30 Various arrangements may be provided to form a mounting for the door latch mechanism. I have shown one simple illustrative arrangement wherein the side member of the frame, adjacent the free edge of the door, 35 is formed with an enlarged or offset portion, 20, which is recessed as indicated at 21. The door latch plate carrying the latch mechanism is received and accommodated in the recess, 21, and is fastened therein, in any convenient manner, as, for instance, to seats or 40 shoulders, 22, provided at the corners of said recess. In order to permit the latch bolt to operate through the free edge of the door, the edge portion of the frame adjacent the mounting for the latch plate is cut away, as indicated at 24, see Fig. 3. To strengthen the frame at this cutaway portion, a laterally and outwardly offset bridge piece, 23, is 45 formed on the frame at this point, see Figs. 3 and 4, so both the web 9 and the flange 16 are offset to provide a mounting for the door-securing device, in this case the lock.
- 50 It is customary to operate the door latch mechanism by means of a spindle which extends transversely through the door and carries the usual handles. To accommodate such a latch operating spindle, I provide the frame with a suitable and convenient spindle bearing indicated at 26, in a boss, 25, with which 55 the frame is provided.
- Various provisions may be made for receiving and supporting a curtain rod on the door frame. One simple and illustrative arrangement for this purpose is shown wherein the 60 inner surface of the top rail of the frame is formed near the free edge of the door with a vertical tapering seat or groove, 27, see Figs. 2, 3 and 9. A plate, 28, is secured over this seat or groove and cooperates therewith to form a vertical socket to receive and support 70 the lower end of a curtain rod. If desired, a thimble or sleeve, 30, flanged, as at 29, over the upper edge of the door, may be inserted into the upper end of the socket, 27, to form a neat finish therefor. This feature, however, may be dispensed with.
- It is customary to equip the free edges of automobile doors with a dovetail member to cooperate with a corresponding member on the body at the door opening in order to 80 secure and insure the proper alignment of the door when it is closed. In accordance with my invention, I provide a mounting for the dovetail member on the door frame. In the illustrative arrangement shown, see 85 Fig. 10, the frame web, 9, at a convenient point at the free edge of the door is formed with a recess or offset indicated at 31, in which the dovetail member, 32, is received and secured. The nut on the bolt, 34, which 90 secures the dovetail member, 32, in place, is accessible from the inner side of the door to permit the removal and replacement of the dovetail member.
- The door hinges may be mounted in many 95 different ways upon the frame. I have shown one simple illustrative mounting wherein the web, 9, of the frame, at suitable points along the hinge edge of the door, is provided with transverse openings, 8, see Fig. 6, through 100 which are received the shanks of hinge members, 39. The nuts, 40, by which said hinge members are secured to the door frame are accessible from the inner side of the door for removal or replacement of the hinge members.
- I have found it convenient, practical and desirable to produce the door frame by casting it, and in order to secure lightness I have used a cast aluminum frame and an aluminum panel, although, obviously, my invention is not to be limited or restricted in this respect.
- A door structure such as above described is not only stiff, strong and durable but it 110 is also remarkably light. It will be seen that I avoid the necessity of welding or soldering the door panel. This greatly reduces the cost of construction and is particularly advantageous and important where aluminum is 115 employed for the panel and frame on account of the difficulties encountered in successfully soldering or welding that metal. It will also be seen that I not only provide simple and efficient means for securing the top edge of 120 the panel to the top rail of the frame but I also employ the same means for securing the upholstery for the inner surface of the door. I am also enabled to secure a very strong 125 and rigid mounting for the latch mechanism 130

since such mechanism is carried by and wholly supported in the door frame. This is also true of the mountings for the curtain rod, the dovetail member and the door hinges, and 5 as the mountings for all these parts are readily accessible from the inside of the door said parts are readily and easily removable and replaceable when so desired.

Many variations and changes in the 10 details of construction and arrangement will readily occur to persons skilled in the art without departure from the spirit and scope of my invention. I do not desire, therefore, to be limited or restricted to the exact details 15 shown and described.

Having thus described my invention, what I claim as new and useful and desire to secure by Letters Patent is:

1. A door for automobile bodies comprising 20 a cast metal frame conforming to the shape of the door, said frame having an offset portion forming a supporting base for door latch mechanism, and a sheet metal panel applied externally to said frame and having marginal portions secured to the 25 frame at the edges thereof.

2. A door for automobile bodies comprising 30 a cast metal frame conforming to the shape of the door, said frame having an offset portion forming a supporting base for door latch mechanism, the edge portion of said frame being cut away adjacent said supporting base and said frame having a reinforcing portion bridging said cut-away portion, and a sheet metal panel applied externally to the frame and having marginal portions secured to the frame at the edges thereof.

3. A door for automobile bodies comprising 40 a cast metal frame conforming to the shape of the door and having an enlarged portion at one edge provided with seats to receive a latch plate and a recess to accommodate the latch mechanism carried by said plate, the edge portion of said frame being cut away to permit passage of the bolt of said latch mechanism and said frame having a portion bridging the recess and offset to pass around the latch mechanism, thus reinforcing the framework at this point, and a sheet metal panel applied externally to said frame and having marginal portions secured to the frame at the edges thereof.

4. A door for automobile bodies comprising 50 a cast metal frame conforming to the shape of the door and provided with an offset portion formed to support the latch mechanism and a second offset portion forming a bearing for a latch actuating spindle, 60 and a sheet metal panel applied externally to said frame and having marginal portions secured to the frame at the edges thereof.

5. A door for automobile bodies comprising 65 a cast metal frame conforming to the shape of the door and having a marginal web

extending transversely to the plane of the door, said web having a plurality of bosses formed therein, a separately formed and applied metal strip secured to one edge of said web and extending beyond said web substantially parallel to the plane of the door, screws threaded into said bosses and securing the strip to the web, and a sheet metal panel applied externally to said frame and having a marginal portion thereof clinched over the 70 projecting edge of said strip.

6. A door for automobile bodies comprising 75 a cast metal frame conforming to the shape of the door and provided with a top rail having an outwardly-facing channel and an inwardly-facing channel, a sheet metal panel applied externally to said frame and having its upper marginal portion bent over said top rail and into said inwardly facing channel, and means for securing said portion 80 of the panel therein.

7. A door for automobile bodies comprising 85 a cast metal frame conforming to the shape of the door and having a top rail provided with a substantially vertical groove 90 therein, a plate secured to the side of said top rail and closing said groove, thus forming a curtain rod socket, and a sheet metal panel applied externally to said frame and having marginal portions secured to the frame at the 95 edges thereof.

8. A door for automobile bodies comprising 100 a cast metal frame conforming to the shape of the door and including a marginal web extending transversely of the plane of the door, said web having an opening therethrough adapted to receive the shank of a hinge member secured to said web, and a sheet metal panel applied externally to said frame and having marginal portions secured 105 to the frame at the edges thereof.

9. In a door structure for automobile 110 bodies, a metal door rail having an offset latch supporting base formed in the body thereof.

10. In a door structure for automobile bodies, a metal door rail having an offset latch supporting base and an offset journal bearing for the associated latch operating spindle, both formed in the body of the rail. 115

11. In a door structure, a metal frame formed with a longitudinally-extending channel in the inner face of the top rail thereof and a metal panel having its upper marginal edge flanged over said top rail and 120 secured in said channel.

12. In an automobile door, a horizontal rail having an upwardly and inwardly curved flange, and upholstery secured to said rail beneath the rear edge of said curved 125 flange.

13. In an automobile door, a horizontal rail having an upwardly and inwardly curved flange, outer paneling clinched over the free edge of said curved flange, and up- 130

holstery secured beneath the clinched portion of said paneling.

14. In an automobile door, a cast metal skeleton frame embodying rails of Z shaped cross-section, the body web and one arm of which are of integral cast metal and the outer arm of which is separately formed of rolled metal and secured thereto.

15. A one-piece perimetral skeleton frame for automobile doors comprising integral 10 top, bottom and side rails, provided with integral offsets for the mounting of the door securing devices.

In testimony whereof, I affix my signature.

JOSEPH LEDWINKA.
